Primary Examiner — Raphael Barkai*Assistant Examiner* — Randall H Gholson(74) *Attorney, Agent, or Firm* — Nelson Mullins Riley & Scarborough, LLP(57) **CLAIM**

The ornamental design of a ratchet wrench, illustrated substantially as shown and described.

DESCRIPTION

FIG. 1 is a perspective view of a ratchet wrench embodying the design of the present invention;

FIG. 2 is a top plan view of the ratchet wrench illustrated in FIG. 1;

FIG. 3 is a bottom plan view of the ratchet wrench illustrated in FIG. 1;

FIG. 4 is a left side view of the ratchet wrench illustrated in FIG. 1;

FIG. 5 is a right side view of the ratchet wrench illustrated in FIG. 1;

FIG. 6 is a top plan view of the ratchet wrench illustrated in FIG. 1; and,

FIG. 7 is a bottom plan view of the ratchet wrench illustrated in FIG. 1.

Broken lines are for illustrative purposes and form no part of the claim.
